UNITED STATES PATENT OFFICE.

STEPHEN W. KOLCZEWSKI, OF BUFFALO, NEW YORK.

DEVICE FOR CATCHING MAIL AND FUEL BY AN AIRPLANE IN FLIGHT.

Application filed June 19, 1918. Serial No. 240,840.

To all whom it may concern:

Be it known that I, STEPHEN W. KOLCZEWSKI, a subject of Russian Poland, who has declared his intention of becoming a citizen 5 of the United States, and a resident of Buffalo, in the county of Erie and State of New York, have invented certain new and useful Improvements in Devices for Catching Mail and Fuel by an Airplane in Flight, of which 10 the following is a specification.

My invention relates to improvements in catching devices it being more particularly in the nature of an improvement in means intended primarily for use on airplanes for 15 catching and hauling objects from the ground to the airplane while the latter is in flight.

An object of my invention is to provide an arrangement of correlated devices located 20 both on the ground and in the airplane, whereby such objects as mail, fuel, etc., may be caught up from the ground and hauled up to the airplane.

A further object of the invention is to 25 provide an arrangement of the class described which includes a guiding device located on the ground with a suitable support for an object such as a bag of mail, a can of fuel, etc., and means carried by the airplane 30 arranged to be let down to sweep toward the contracted throat of the guiding device toward the object to catch it up, whereupon the object is hauled up to the airplane.

Other objects and advantages will appear 35 in the following specification reference being had to the accompanying drawings in which:

Figure 1 is a diagrammatic plan view illustrating the invention,

Figure 2 is a detail plan view of a portion of the guides and the object carrying platform,

Figure 3 is a side elevation of the guides 45 shown in Figure 1,

Figure 4 is a side elevation of the parts shown in Figure 2,

Figure 5 is a detail view hereinafter described,

Figure 6 is a perspective view showing the 50 object suspending ring with a mail pouch suspended therefrom.

Figure 7 is a detail sectional view on the line 7—7 of Figure 6,

Figure 8 is a plan view of the suspending 55 ring showing the entrance open,

Figure 9 is a section on the line 9—9 of Figure 8,

Figure 10 is a longitudinal section of the suspending ring showing the entrance 60 closed,

Figure 11 is a cross section on the line 11—11 of Figure 8,

Figure 12 is a front elevation of the ring 65 with the entrance closed,

Figure 13 is a detail plan view of the airplane-carried hoisting mechanism,

Figure 14 is a sectional view of the airplane body showing the hoisting mechanism on the inside, 70

Figure 15 is a detail plan view of the reversing mechanism,

Figure 16 is a detail view of the driving mechanism,

Figure 17 is a detail view of a safety 75 catch used in connection with the hoisting drum,

Figure 18 is a sectional view of the catching ball suspended from the airplane, showing the shock absorbing mechanism on the 80 inside, and

Figure 19 is another sectional view of the catching ball.

By way of preface the object of the invention may be briefly stated as being intended to provide simply constructed devices carried both by an airplane and located at suitable places on the ground, by means of which the aviator may practically reach down and gather up such intended or necessary articles as a mail pouch or a supply of fuel. In order that the various parts of the invention may be fully understood, attention is first directed to the guides which consist in the present instance of a 85 pair of walls 1. These walls as is clearly shown in Figure 1, converge to a constricted outlet or throat 2 through which the cable 3 which hangs from an airplane by virtue of the catching ball or gripping means 4, is 95 arranged to pass and catch up an object such as a mail pouch or a can of fuel.

A platform 5 serves as a support for an object of the nature described. In the present instance this object consists of a mail pouch 6. The foregoing description indicates that a variety of objects may be placed 105 on the platform to be caught up. Suitably

designated fuel stations may be located along an airplane mail route so that if the aviator finds himself short of fuel he may practically reach down and gather up a fresh supply.

The illustration in Figure 4 indicates that the invention is intended primarily to be used in connection with an airplane mail route. In actual practice the mail stations 10 will consist of such arrangements as shown in Figure 1, whereby the mail pouches from the various stations along the route may be gathered up without involving the necessity of landing at each station. This is a 16 general statement of the purpose of the invention and this being now understood, attention is again directed to the construction of the guides.

These consist of walls which are made of 20 any suitable material such as wire netting as shown in Figures 3 and 4. The upper edges are reinforced by angle irons 7 which extend forwardly in a horizontal plane above and beyond the sloping members 8 25 which reach forwardly into proximity to the place where the mail pouch 6 is located. This sloping portion provides an outlet for the ball 4. The walls 1 are supported by suitably trussed standards 9, and the entire 30 structure is further braced by guy cables 10 which are arranged in any suitable manner. Supported on the forwardly projecting portions of the angle irons 7 is the releasing mechanism which comprises a hinge connection 35 11 by means of which the hinged ring supporting plates 12 are mounted. These plates are thus hinged in order to impart a certain amount of flexibility to the releasing mechanism. The ball 4 in departing from 40 the outlet 8 has a tendency to move in an oblique direction as indicated in Figure 5. This upward movement of the ball is partly expended on the releasing mechanism which by virtue of the hinge connection 11 swings 45 upwardly as shown in Figure 5 to allow the removal of the mail pouch and more particularly its suspending ring without binding or breaking any of the parts.

Mounted on laterally projecting arms 13 50 are leaf springs 14 with lugs 15. Each lug includes a recess with an inwardly projecting lip. The recess receives a boss 16 of the pouch suspending ring 17, and the lip forms a support for the boss in each instance. A 55 latch 18 is pivoted at 19 to one of the supporting plates 12. A leaf spring 20 beneath the latch tends to press it upwardly.

A pivoted releasing arm 21 extends across the throat 2 in the path of the cable 3. When 60 the arm 21 is engaged by the cable, it is swung on its pivot so as to cause the head 22 to ride backwards and release the latch 18 whereupon the latch springs upwardly by virtue of the spring 20 beneath it. The 65 latch has a roller 23 which lessens the fric-

tion in riding over the inclined surface of the head 22.

Guards 24 fixed on the hinged portion of the releasing mechanism, enable the separation of the suspending ropes 36 to keep the 70 passage of the ball 4 clear. Stops 25 support the hinged releasing mechanism in the normal position illustrated in Figure 4.

The suspending ring 17 is hollow as shown in Figure 10 and is separated to provide an 75 entrance 26. The entrance coincides with the throat 2 when the ring 17 is set in position on the releasing mechanism, so that the cable 3 may enter the ring and enable the suspension of the mail pouch 6 from the airplane by virtue of the ball 4. The ball 4 is larger than the opening in the ring as indicated in Figure 5.

On the inside of the ring 17 there is a 80 spring 27 which abuts a stop 28 at one end and presses against a lock 29 at the other. The lock 29 has a notch 30 which is occupied by the nose 31 of the latch 18 when the lock is in the retracted position. At this time, the entrance 26 is open. The retracted and 85 latched position of the lock 29 is indicated in Figure 8. The operation of the releasing arm 21 by the cable 3 as formerly described, serves to release the lock 29 by the release of the latch 18, whereupon the entrance 26 90 is closed to prevent a possible escape of the cable 3.

A pin 32 carried by the lock 29 works in a 95 slot 33 on the inner periphery of the ring 17. This arrangement prevents any tendency of the lock to turn. A catch 34 on the other side of the ring holds the lock 29 in the other extremity of its two positions as shown in Figure 10. The catch 34 is retracted against the tension of a spring and 100 to release the catch head of the lock, by a finger piece 35 which is exposed on the inside of the ring as shown.

Ropes 36 support the mail pouch 6 from 105 the suspending ring 17. These ropes are 110 preferably of wire and are fixed in the equidistantly spaced suspending lugs 37 by means of the arrangement shown in Figure 7. Each of the lugs has a thimble 38 which 115 is swaged in the lug. The thimble widens out into a cup-shaped top which is occupied by the knotted end of the rope. Solder is poured into this cup shaped top and around the knotted end thus uniting the rope and the thimble. A similar arrangement obtains at the lower ends of the ropes 36 where they are joined with the jaws of the mail pouch 6.

The catching ball 4 has a drum 39 on the 120 inside, upon which the lower end of the cable 3 is wound. The drum 39 rotates on a shaft 40 and has suitable roller bearings by means of which the drum is made to rotate freely. A similarly mounted guide spool 41 guides 125 the cable 3 on the drum. Springs 42 which 130

act on the drum 39 by virtue of a connecting rod 43, keep the cable 3 wound on the drum 39. The end of the cable it is to be observed, is fixed in the drum by the same means employed to secure the ropes 36 in Figure 7.

The mechanism just described is intended to absorb the shock of the impact of the catching ball 4 on the releasing mechanism. It can be readily understood that an airplane moving forwardly at a tremendous speed might readily tear the releasing mechanism apart were the shock absorbing mechanism inside of the catching ball not provided. When the ball 4 engages the suspending ring 17 and the travel of the ball is temporarily impeded, the cable 3 will lengthen by virtue of the unwinding of the drum 39. This occurs against the tension of the springs 42. The mail pouch having been freed from the releasing mechanism, it is drawn up to the airplane by the hoisting mechanism which is carried thereby. The upper end of the cable 3 is wound on a drum 44. The hoisting drum is mounted on a shaft 45. One end of the shaft carries the rotating and reversing mechanism illustrated in Figure 15. A pair of bevel gears 46, 47 are splined on the shaft 45. These are alternately engaged by a drive pinion 48 which is driven from the motor crank shaft 49 by means of the flexible shaft 50. The shaft 50 is flexible in that it includes a universally coupled member and a member operating in a plane below the crank shaft 49.

Disposed between the bevel gears 46, 47 is a spring 51 which presses them apart and against adjacent shifting arms 52, 53. Each arm has a boss 54 which cooperates with the boss 55 on a yoke 56. The yoke is mounted on the shaft 45, embraces the reversing mechanism carried thereby and provides a bearing for the shaft of the driving gear 48. The coacting surfaces of the bosses 54 and 55 on the arms and yoke respectively, are formed into cooperating lugs and recesses which have straight and inclined end walls. When both arms 52 and 53 are moved rearwardly, the lugs and recesses on both sides engage by virtue of the pressure of the spring 51. This indicates a neutral position where no driving action occurs.

When the arm 52 is pulled forwardly as shown, the inclined walls of the lugs ride up the inclined walls of the recesses in the boss 55 so that the bevel gear 46 is pressed inwardly into engagement with the driving gear 48. This causes the drum 44 to either wind up or pay out the cable 3 according to the direction of the rotation of the shaft 45. The same operation takes place when the other handle is pulled forwardly, but the drum 44 of course rotates in the opposite direction.

65 The shaft 50 commences its rotation simul-

taneously with the operation of either handle in the forward direction. Ordinarily when the handles are pressed rearwardly, the shaft 50 does not rotate. This simultaneous operation is brought about by means of a flexible connection 57 between the lower end of each handle and a flexible member 58 which is connected to a toggle lever 59. Toggle links join the lever with toggle arms 60 at either side of the pivot of the toggle lever. The toggle arms are hinged together at the top and when tension is applied to the member 58 through either of the flexible connections 57, the toggle arms 60 are drawn toward each other by virtue of the toggle lever 59 and against the tension of springs 61. These springs normally separate the arms 60.

The end of the crank shaft 49 extends between the arms 60. Rollers 62 carried by one toggle arm are arranged to engage the shaft at one side. A friction roller 63 carried by the other toggle arm is arranged to engage the shaft on the other side. The speed of rotation of the shaft 50 is reduced from that of the crank shaft 49 by means of the reducing gears 64 which are geared up to the friction roller 63. The seat 50^a occupied by the observer and located near the reversing mechanism, is reversible as shown so that he may readily turn around and operate the mechanism when required.

In the event of a breakage of any of the parts of the reversing mechanism, the safety device illustrated in Figure 17 is operated. When the hoisting drum 44 is operated, the observer presses on the dog 65 so that the ratchet 66 on the end of the drum is disengaged. Should a breakage occur during the hoisting operation, the rotation of the hoisting drum is checked by releasing the dog 65 when it flies into contact with the ratchet 66 by means of the spring beneath the treadle end thereof.

The operation.—Any desired number of the V-shaped guides illustrated in Figure 1 are located at stations on the ground. A mail pouch 6 or in fact any other object, that is to be transmitted to an airplane, is set on the platform 5.

The mail pouch 6 has a suspending ring 17 which is clamped in position in the releasing mechanism of the V-shaped guide by means of the pressure of the lugs 15 against the bosses 16. The releasing mechanism is hinged as shown and the suspending ring remains in the position indicated in Figures 2 and 4 until an airplane comes along.

The observer turns around in his seat, pulls the handle 53 so that the hoisting drum 44 is rotated to pay the cable 3 out. This lowers the catching ball 4 into a plane below the throat 2. The cable 3 finally strikes the releasing arm 21 of the releasing mecha-

nism. The latch 18 thus becoming disengaged by the head 22, flies upwardly by virtue of the spring 20. The lock 29 of the ring 17 is thus freed and springs across the entrance 26, locking the cable inside of the ring. The ball 4 is larger than the central opening of the ring 17 and thus becomes the suspending or gripping member for the mail pouch 6 from the airplane.

10 The advantages of the shock absorbing mechanism inside of the catching ball 4 have already been described at length. The cable wound on the drum 39 inside of the ball, unwinds when the drum rotates against the tension of the springs 42. This freedom of movement is what absorbs the shock of the impact of the ball on the releasing mechanism. The upward and oblique movement of the suspending ring 17 as it departs from the releasing mechanism, is taken care of by hinging the releasing mechanism so that it may swing upwardly as illustrated in Figure 5.

While the construction and arrangement 25 of the device as herein described and illustrated is that of a generally preferred form, obviously modifications and changes may be made within the scope of what is claimed without departing from the spirit of the invention, or the scope of the claims.

I claim:

1. Supply means for aircraft, comprising 30 guide means including a throat, releasing mechanism located at said throat and including a pair of spring arms arranged to hold a suspending ring of a receptacle in position, said suspending ring having an entrance in coincidence with said throat for receiving a weighted cable pendent from an 40 airplane, and bosses carried by said ring engaged by said spring arms to hold the ring in position and enabling the releasing of said ring from the releasing mechanism when the weight on the cable engages the 45 ring.

2. In a device of the class described, guide means including a throat, a platform arranged adjacent to said throat, releasing mechanism mounted adjacent to said throat, 50 means embodied in said mechanism for supporting a suspending member of a receptacle resting on the platform, said suspending member having a cable entrance coinciding with the throat, means embodied 55 in said member for closing the entrance, and means carried by the releasing mechanism normally holding said entrance closing means in a retracted position and arranged to be operated by a cable with a gripping means, to release said entrance closing means and prevent the cable from escaping from the ring after the gripping means is in position.

3. Supply means for aircraft, comprising 60 guide means with a throat, including for-

wardly projecting portions, releasing mechanism including ring supporting plates mounted on said forwardly projecting portions, laterally extending arms, resilient holding means mounted on said arms including leaf springs having lugs with recesses and lips, said recesses and lips being arranged to receive and support bosses of a suspending ring said ring having an entrance coinciding with the throat, a spring 70 pressed lock with a notch operating in said ring and arranged to close said entrance, means including a latch embodied in the releasing mechanism arranged to engage the notch and hold the lock in the retracted position to leave the entrance of the ring open, and means including a pivoted releasing arm including a portion bearing on the latch and holding it in the lock retaining position and a portion bridging the throat to be engaged by an airplane-carried cable passing through the throat.

4. Supply means for aircraft, comprising 75 guides including a throat, a platform, releasing mechanism pivotally mounted at the end of the throat, resilient means embodied in said mechanism for supporting the suspending ring of a receptacle on the platform said receptacle and ring being joined by ropes, said ring having an entrance coinciding with the throat to admit an airplane-carried cable having a catching ball to engage the ring and remove it from said resilient supporting means, and means including 80 guards carried by the releasing mechanism for separating certain of the ropes to prevent entanglement of the catching ball.

5. In a device as described, guides including 85 angle irons bounding the upper edges and terminating in a contracted throat, forwardly extending inclined portions below the members of said throat, a releasing mechanism hingedly mounted on the members of said throat and disposed above said inclined portions, holding means embodied in said releasing mechanism including a pair of spring arms having lugs with recesses and lips for receiving and holding the bosses of a suspending ring having a rope-attached receptacle resting on the platform, said ring being separated to form an entrance coincident with the throat, a spring actuated lock in the ring arranged to close the entrance, retractible means for latching the lock in the locking position, guards for keeping certain of 90 said ropes separated, a latch carried by the releasing mechanism with a nose for holding the lock in the retracted position, a spring for pressing the latch upwardly, a roller carried by the latch, and a releasing arm pivoted on the releasing mechanism including a head with an inclined portion cooperating with said roller and including a portion reaching across said throat to be engaged by an airplane-carried cable in sweep- 95 100 105 110 115 120 125 130

ing toward the suspending ring, said releasing arm then disengaging the latch and freeing said lock.

6. In a device of the class described, guide means elevated above the ground on posts, converging into a narrow passage, spring arms arranged at the narrow passage to hold a receiving device having a narrow entrance leading to a larger opening in the center, said 10 receiving device being connected with a receptacle arranged to contain mail, said receiving device being held under the ends of said guides at the narrow passage to bring the narrow opening and said passage into communication, said passage and opening being arranged to receive a cable suspended from aircraft with a ball secured to the end of said cable, said ball being larger than the center opening of the receiving device so as 15 to pull said receiving device away from its support.

7. In a device of the class described, guide means including a narrow passage, spring arms arranged to hold a receiving ring with a narrow entrance, said ring being held by said spring arms under the ends of said guides at the narrow passage to bring the narrow opening of said ring into communication with said passage, a lock in the ring, a spring 20 for actuating the lock, a latch for holding the lock in a retracted position, said latch having a roller, a releasing arm pivoted at one end to said guides, having a shorter end shaped to have a narrow flat space on the 25 bottom with an incline on the side said narrow flat space engaging the roller, the longer end of said arm extending across the narrow passage and in back of the ring entrance, said arm being actuated by a passing 30 cable suspended from aircraft causing the rocking of the arm and the release of the latch and enabling the closing of the ring entrance by the lock, and a ball carried by the cable, of a diameter larger than the 35 opening in the ring to cause the pulling away of the ring.

8. In a device of the class described, guide means with a narrow passage, a pair of spring arms arranged to hold a receiving ring with a narrow entrance, said ring being held by said spring arms under the ends of said guides at the narrow passage to bring the narrow opening of said ring into communication with said passage, a lock in the ring, a spring 50 for actuating the lock, a latch for holding the lock in a retracted position, said latch having a roller, a releasing arm pivoted at one end to said guides, having a shorter end shaped to have a narrow flat 55 space on the bottom with an incline on the side said narrow flat space engaging the roller, the longer end of said arm extending across the narrow passage and in back of the ring entrance, said arm being actuated by a passing cable suspended from aircraft 60

causing the rocking of the arm and the release of the latch and enabling the closing of the ring entrance by the lock, a ball larger than said opening carried by the cable, to cause the pulling away of the ring from said 70 spring arms, the other end of said airplane carried cable being wound on a drum shaft in the aircraft, said shaft being arranged to be driven to wind up the cable and draw the suspending ring with the receptacle to 75 the aircraft.

9. In a device of the class described, a pair of guides elevated above the ground on posts, said guides being set in a V formation and converging into a narrow passage, a pair of spring arms arranged to hold a receiving ring with a narrow entrance, said ring being held by said spring arms under the ends of said guides at the narrow passage to bring the narrow opening of said ring into communication with said passage, a lock in the ring, a spring for actuating the lock, a latch for holding the lock in a retracted position, said latch having a roller, a releasing arm pivoted at one end to said guides, having a shorter end shaped to have a narrow flat space on the bottom with an incline on the side said narrow flat space engaging the roller, the longer end of said arm extending across the narrow passage and in back of the ring entrance, said arm being actuated by a passing cable suspended from aircraft causing the rocking of the arm and the release of the latch and enabling the closing of the ring entrance by the lock, a ball carried by the cable, of a diameter larger than the opening in the ring to cause the pulling away of the ring from said spring arms, 80

the other end of said airplane carried cable being wound on a drum shaft in the aircraft, said shaft being arranged to be driven to wind up the cable and draw the suspending ring with the receptacle to the aircraft, a reversing mechanism comprising bevel gears on said shaft, a bevel driving gear, a flexible shaft for said driving gear, a spur gear on the other end of said shaft, driving mechanism cooperating with said spur gear including friction pulley devices arranged to engage the end of the crank shaft of an airplane motor, toggle arms supporting said driving mechanism and arranged to convey the friction pulley into contact with the end of the crank shaft of an airplane motor, a pair of pivoted arms having cams coacting with cams on the bevel pinions to shift one or the other of said pinions into engagement with the driving pinion upon the movement of the corresponding arm, flexible connections between the short ends of said arms and said toggle arms to secure the simultaneous rotation of the shaft with the shifting of the companion bevel pinion, and means coact- 85

ing with the winding drum for preventing the unwinding of the cable in the event of a breakage in the hoisting mechanism, said means including a ratchet on the winding shaft and a pivoted spring pressed dog.

10. Supply means for aircraft, comprising catching means swung from the aircraft, means arranged to support supplies and direct said catching means to the point of support of the supplies, clamping means located at said point, means carried by the bag and temporarily held by said clamping means, including a normally open ring closable by a latch; and means associated with said clamping means for holding the latch retracted to admit a part of said catching means, whereupon said latch holding means is engaged to release the latch as the ring departs with the bag catching means.

11. Supply means for aircraft, comprising an anchor to which the supplies are attached, said anchor having a receiving throat; means for normally holding said anchor but permitting detachment thereof, means depending from an aircraft, including gripping means; means for guiding said depending and gripping means into the anchor throat, and means for closing the throat to prevent the loss of the supplies from said anchor by a loosening of said anchor and a relaxation in the tension of said depending means.

12. Supply means for aircraft, comprising an anchor, a flexible tie for connecting the supplies to said anchor, means for normally holding said anchor but permitting ascent thereof, said flexible tie passing over said holding means; a cable with gripping means depending from the aircraft, said anchor having a throat adapted to receive said cable and be engaged by said gripping means, means for guiding said cable into said throat, and means for preventing departure of said gripping means from said throat upon relaxation of tension in said cable.

13. Supply means for aircraft, comprising an anchor with a receiving throat, re-

silient and upwardly movable means for supporting the anchor, and means depending from the aircraft, with gripping means to disengage the anchor from its supporting means after the depending means enters the throat.

14. Supply means for aircraft, comprising an anchor with a receiving throat, resilient means for supporting the anchor, means depending from the aircraft, with gripping means to disengage the anchor from its supporting means after the depending means enters the throat, and means including a releasing arm, actuated at substantially the same time to free a lock for the closure of the throat.

15. Supply means for aircraft, comprising an anchor with a throat, a lock embodied in the anchor, and supporting means for the anchor including means for holding the lock retracted from the throat while the anchor remains on the support.

16. Supply means for aircraft, including a member pendent from an aircraft, means carried by said member for engaging the supplies, and means embodied in said carried means for absorbing the shock of engagement with said supplies.

17. Gripping means for aircraft, including a cable pendent from an aircraft, supply gripping means carried by the cable, comprising a casing containing means on which the cable is wound, and associated cable-releasing mechanism for gradually paying out a certain length of cable on engagement of supplies by said gripping means, to absorb the shock of engagement.

18. Supply means for aircraft, including a cable pendent from an aircraft, supply gripping means carried by the cable including a casing with a drum having the cable wound thereon, and tension means in connection with the drum, against which a certain length of cable pays off from the drum upon engagement of supplies by the gripping means, to absorb the shock of engagement.

STEPHEN W. KOLCZEWSKI.
